UNITED STATES PATENT OFFICE.

MORGAN D. SADTLER, OF BALTIMORE, MARYLAND.

WRENCH.

1,199,823.

Specification of Letters Patent.

Patented Oct. 3, 1916.

Application filed January 26, 1916. Serial No. 74,377.

To all whom it may concern:

Be it known that I, MORGAN D. SADTLER, a citizen of the United States, residing at Baltimore, State of Maryland, have invented certain new and useful Improvements in Wrenches, of which the following is a specification.

This invention relates to improvements in wrenches.

10 The object of the invention is to provide a wrench which will have great range of usefulness, and one in which it will not be necessary to use the handle or casing for the driving shaft, as a lever to actuate the 15 wrench, thereby making the wrench available for applying or removing nuts in difficult or out of the way places in machinery.

I am aware that it is not new to drive nut seaters by gears, but in devices of this character, so far as I know, there is no means provided for preventing the gears from meshing too tightly and especially when the wrench is being operated.

One of the objects therefore, of this invention, is to provide a construction wherein the gears will, at all times, be kept in mesh to the same degree, regardless of the amount of pressure or force applied to them, in applying or removing the nut, thereby 30 preventing wear and longitudinal movement of the gear bearings.

A further object of the invention is to provide in addition to a wrench adapted for engagement with the wrench end or nut engaging member, a member equally well adapted for receiving the ends of drills, bits, etc., which adapts the device to be used as a boring or screw unseating tool.

40 A still further object of the invention is to provide in connection with the driving shaft of the wrench, a handle adapted to fit in the end of a shaft, the handle being provided with a plurality of apertures for engagement with the driving shaft, to vary 45 the leverage in applying or removing the nut or other object upon which the device is adapted to operate, as the exigencies of the case may require.

In the drawings, Figure 1 is a perspective view of the wrench with the handle attached to the driving shaft. Fig. 2 is a longitudinal sectional view of the wrench showing the means for keeping the driving gears in proper mesh or for limiting the longitudinal movement of the gears. Fig. 3 is a perspective view of a nut engaging end of

the well known variety in connection with which the wrench is particularly designed for use. Fig. 4 is a detail perspective view of the means for keeping the gears in proper 60 mesh.

Referring to the drawings, the numeral 1 designates the driving shaft casing. This is threaded at one end as indicated at 2 for the reception of a collar 3 internally threaded 65 for the reception of the casing 1. This collar is formed with a boss 4 provided with external threads 5, which engage internal threads 6, on the hollow angle member 7. The numeral 8 designates the driving shaft 70 provided at its outer end with a squared portion 9 adapted to enter one or the other of a series of squared apertures 10 in the operating handle 11. The opposite end of the shaft has rigidly secured thereto a bevel 75 gear 12 at the rear of whose teeth is arranged a short flange 13 which forms a part of the boss 14 of the gear 12, so that when the parts are assembled, as shown in Fig. 2, the boss will fit snugly within the collar 3, 80 with the flange against the inner edge of said collar, thus preventing outward movement of the gear. In mesh with the gear 12 is another bevel gear 15, carried by the inner end of a stub shaft 16, which extends through 85 and has bearing in a collar 17, the reduced portion of which is threaded as indicated at 18 for engagement with the internal threads 19 in the other end of the angle member, thus supporting the gears and connected 90 parts at right angles to each other. The outer end of the stub shaft 16 is squared as indicated at 20, to adapt it for entry into the squared opening 21, in the nut engaging 95 end 22, which as before stated, may be of any of the well known or approved forms, and adapted for engagement either with squared or polygonal nuts, it being understood that in these nut engaging members, the socket is of standard size, regardless of 100 the size of the nut for which the nut receiving aperture is adapted. The squared portion of the stub shaft 16 is provided with a socket 23 for the reception of the tang of a drill or other similar tool, as would be desired in case the wrench is converted into a 105 boring tool.

The numeral 24 designates a spider, preferably integral with the angle member 7, with two points 25 and 26 arranged at right 110 angles to each other, the point 25 engaging the bevel gear 12 centrally, while the point

26 engages the gear 15, similarly, thus keeping the gears in proper and uniform mesh at all times, resisting any tendency of the gears to climb or wedge under excessive pressure, thereby eliminating wear and producing absolute uniform rotation of the driving member under all conditions. In the present instance, four arms of the spider are shown, two of which are centering members for the gears, and the other two as retaining members with the angle member 7.

10 The term "nut-seating" member is to be understood generically as comprehending a member that will seat a nut or drive a drill, screw driver or the like.

15 Having thus described my invention, what I claim is:—

1. A wrench embodying gear-actuated driven and driving members, and fixed 20 means engaging axially with the members to prevent end-thrust and thus over-meshing thereof.

2. A wrench having means whereby a nut can be seated at an angle to the member 25 receiving it, and means for presenting axial resistance to lost motion or back-lash between the driving and driven members whereby undue wear or uneven action of the actuating members will be secured irrespective of torsional or tensile strain.

3. A wrench embodying a nut seating member, an actuating member arranged at an angle thereto, and means for presenting axial resistance to lost motion or back-lash 35 between the driving and driven members whereby the union between the actuating members will be maintained irrespective of pressure and torsional strain.

4. A wrench comprising a nut seating member provided with a gear, a driving member having a gear meshing with that of the first named member and means for presenting axial resistance to lost motion or back-lash between the driving and 45 driven members for maintaining the two gears in predetermined intermesh relation, irrespective of conditions of use.

5. A wrench comprising a rotatable nut seating member having a bevel gear thereon, a driving shaft at right angles to said nut seating member and carrying a bevel gear

in mesh with the first mentioned gear, and means engaging the centers of the gears to keep them in uniform predetermined mesh.

6. A wrench comprising a rotatable nut 55 seating member having thereon a bevel gear, a driving shaft at an angle to said member and carrying a gear in mesh with the first mentioned gear, and a spider arranged within the angle of the gears and contacting 60 with the centers thereof, whereby the gears are kept in uniform and predetermined mesh.

7. A wrench comprising a hollow curved member, a tubular member connected therewith, a nut seating member arranged within the curved member and provided with a gear, means carried by the latter member for maintaining the nut seating member in position, a shaft arranged in the tubular 70 member and having a gear meshing with that of the nut seating member, means for centering the two gears relative to each other irrespective of the conditions of use, and means for engaging the shaft whereby to impart rotary motion thereto to drive the nut seating member in either direction.

8. A wrench comprising a tubular shank, and a curved elbow, a shaft mounted within the shank and carrying a bevel gear, a nut actuating member journaled within the elbow and provided with a gear meshing with that on the shaft, and means for maintaining the gears in fixed intermeshed relation irrespective of strain or pressure.

9. A wrench embodying a tubular shank and a curved elbow, a shaft mounted within the shank and carrying a bevel gear, a nut seating member journaled in the elbow and carrying a gear meshing with that on the shaft, means for preventing tendency of either the shaft or nut seating member to change their relative axial movements under operation, and means for maintaining the parts in fixed but detachable relation to 90 each other.

In testimony whereof I affix my signature in presence of two witnesses.

MORGAN D. SADTLER.
